UNITED STATES PATENT OFFICE

WALTER C. ELZE, OF FOREST HILLS, NEW YORK, ASSIGNOR TO HAUCK MANUFACTURING COMPANY, OF BROOKLYN, NEW YORK, A CORPORATION OF NEW YORK

PORTABLE TORCH

Application filed April 22, 1930. Serial No. 446,213.

The invention relates to a novel burner member which is adapted for various purposes and is designed to burn low-grade liquid fuels, such as ordinary heavy fuel oil, kerosene, and the poorer grades of gasoline. The novel burner or torch is particularly suitable for the destruction of vegetation, as weeds, and for the extermination of insect pests and their larvae and eggs, as well as the disinfection of fox pens and runs, hen houses, dog kennels, etc.; also, in the removal of snow and ice from railway switches and the like, and for other thawing purposes.

It has for its object to provide a one-man outfit of this type which may conveniently be manipulated and which is readily portable. A further object of the invention resides in the provision of a pilot flame and the arrangement whereby a draft is induced to direct the pilot flame across a nozzle member of the torch; and a still further object resides in an arrangement whereby the relation between the said nozzle member and a surrounding hood may be adjusted to afford various shapes of flame.

In carrying out the invention, a liquid fuel supply tube affords a support for the torch elements and provides as well for a handle or grip portion suitable for manipulating the apparatus. This tube, moreover, is adapted for connection, as by means of a flexible hose or the like, with a suitable source of fuel supply such as a tank or container which may either rest upon the ground or be carried upon the back of an operator of the torch. The said tube terminates at its outer end in a suitable nozzle element through which the fuel is delivered in finely divided state, as by exerting the required pressure behind the same in the tank or container in manner well understood.

A pilot flame is provided in connection with the nozzle to maintain the ignition of the fuel irrespective of the nozzle position, and in certain instances is designed also to preheat the fuel to be delivered from the nozzle. To this end, a hood or housing member is caused to surround the said nozzle, the same being provided with an air port at

the rear and an outlet orifice at the front and is arranged to receive also a wick member designed to be located in juxtaposition to the nozzle. The said wick member in turn communicates with a suitable wick and fuel reservoir which is adjustably mounted on the fuel supply tube behind the hood.

A series of inlet openings is provided in the hood in proximity to the wick to induce a secondary stream of inflowing air for supporting the combustion and for directing the flame of said wick across the path of the fuel projected from the nozzle orifice. The secondary air flow is arranged, moreover, to enter in a direction inclined to the pilot flame so as to better direct or bend it across the nozzle and induce a flow through the hood toward its outlet, resulting in more complete combustion and a more extended flame.

By arranging the wick and fuel reservoir to be adjustable relatively to the said nozzle member, the effect of the pilot flame thereon may be varied, while variations in the flame may be attained by adjusting the hood on the wick tube to elongate said flame or to flare it.

The nature of the invention, however, will best be understood when described in connection with the accompanying drawings, in which:

Fig. 1 is a side elevation of the novel torch member and portion of supply hose connection thereto.

Fig. 2 is a partial longitudinal section, on an enlarged scale, of the burner head.

Fig. 3 is a front elevation of the torch.

Fig. 4 is a fragmentary longitudinal section of the burner head illustrating a modification.

Figs. 5 and 6 are respectively a longitudinal section and a transverse section of a suitable nozzle member for use in the torch.

Referring to the drawings, 10 designates an elongated fuel supply pipe which is adapted for connection at one end to a suitable source of combustible liquid, as may be contained in a readily portable tank or other container (not shown); for example, one which may be strapped to the back of an operator

or manually conveyed from place to place and to which connection may be made from the pipe end through a flexible hose 11. A strain-
5 er 12 may be included in the fuel supply pipe, as well as a controlling valve 13 having the operating trigger 14 whereby the amount of fuel to be fed may be controlled. It will be understood that the fuel is supplied under suitable pressure in the usual and well-known
10 manner so that the same will be forced through the pipe 10 to its outer or burner end at which is provided a nozzle member 15.

This nozzle member may be of any well-known or special design to deliver the fuel
15 in a sufficiently finely-subdivided condition to effect its ready combustion when mixed with air. For example, as indicated in Figs. 5 and 6, the nozzle member may comprise a cylinder 16 axially bored from its inner end,
20 which inner end is threaded to receive the fuel pipe 10. A cap member 17 is threaded over the outer end of the cylinder 16, which outer end is of reduced diameter to afford an annular chamber 18 between the wall of
25 cap 17 and the head of cylinder 16.

Into this annular chamber is designed to be delivered the fuel as through ports 19 extending from the axial bore of the said cylinder. These ports are preferably inclined
30 outwardly; and the inner surface of head 17 as well as the outer surface of cylinder 16 are beveled and cone-shaped and juxtaposed to form a contracted circular orifice 20 for discharge of the fuel substantially to the longitudinal axis of the cylinder and head. The latter is also provided with a flaring orifice 21 in the aforesaid axis, whereby the fuel being discharged is caused to make substantially a right-angle turn. By suitably setting
35 the head 17 with respect to cylinder 16 the orifice opening 20 may be varied and the velocity of discharge through the said orifice may be regulated to suit conditions.

About the nozzle member, and the outer
40 portion of the tube 10 to which it is connected, is an enclosing shell or hood member 25; and through an air supply opening 26 in the rear wall thereof the said supply tube extends. This hood is preferably slightly
45 rounded and turned upwardly at its lower forward end, as indicated at 27, in order to provide a convenient rest shoe and flame-directing portion in the operation of the burner; and it is also provided with an outlet orifice 28 at said forward end, as well as with a series of perforations 29 circularly arranged over its lower surface and inclined toward the said orifice.

The fuel supply pipe for the ready manipulation of the burner apparatus carries an enlarged grip or operating handle portion 10' slidably located some distance behind the said hood and at a point, for example, to effect a substantial balance of the apparatus when
55 held thereat.

Between the hood 25 and handle portion 10' and also mounted about the supply pipe 10 is located a wick and fuel reservoir 30, the same having a tubular extension 31 from its lower portion which projects through the rear wall of the hood 25 beneath the pipe 10. The said hood is shown adjustably secured to this extension as by means of the set screw 32, whereby the position of the nozzle 15 may be fixed relatively to the outlet orifice 28 of the hood.

The reservoir 30, moreover, is designed to retain a secondary supply of fuel, which may be introduced thereto through the filling plug 33 of said reservoir, and a wick 34 therefrom is adapted to be saturated by the secondary fuel and to project slightly beyond the end of the tubular extension 31 in proximity to the nozzle member 15. Reservoir 30 is, preferably, also adjustable, being mounted upon or secured to a sleeve 35 which is slidable over the supply pipe 10. It may be fixed thereto, as through a set screw 36, whereby it becomes possible to locate the reservoir in various positions relatively to the nozzle member 15 which is thus not only adjustable relatively to the wick 34 but also to the said hood. By this expedient, various types of flames are attainable depending upon the relative location of the two said elements, namely the nozzle member and the hood.

Generally, the wick is located substantially in the plane of the orifice 21 of the nozzle member or slightly behind the same so that the pilot flame of said wick will be directed across the jet of fuel issuing from said orifice 21. This action is enhanced and maintained by the induced draft of air entering through the perforations 29 beneath said wick, as well as by the jet effect of the issuing fuel drawing air through the opening 26. The inclination of these perforations serves, furthermore, to encourage the forward flow of air from the rear of the hood, and the rounded unturned bottom at the orifice end of the hood further accentuates this effect.

Ignition of the combustible liquid is thus insured under all conditions; and the pilot flame tends, moreover, to preheat the vapor issuing from the nozzle member. Also, due to the adjustability of the various elements, as aforesaid, a long concentrated flame or a short flaring flame may be had, as desired.

Under certain conditions, it may be desirable, in order more effectively to preheat the vapor delivered by nozzle member 15 to increase the length of pipe portion within the hood 25 and immediately behind said nozzle member as by providing it in the form of a coil 40, while the tubular extension 31 from the reservoir 30 is then withdrawn, as indicated in Fig. 4, to the back of the hood to direct the pilot flame from its wick across the lower surface of the coil.

I claim:

1. A portable torch, comprising a fuel supply tube, a nozzle element at the outer end of said tube, a hood enclosing the nozzle element, mounted over the tube and open at its outer end, a wick and fuel reservoir mounted on said tube and having a tubular extension projecting through the rear of said hood, and a wick extending from the tubular extension and cooperating with the nozzle element.
2. A portable torch, comprising a fuel supply tube, a nozzle element at the outer end of said tube, a hood enclosing the nozzle element, mounted over the tube and open at its outer end, a wick and fuel reservoir mounted on said tube and having a tubular extension projecting through the rear of said hood, and a wick extending from the tubular extension and cooperating with the nozzle element, and the hood being provided with inlet openings in proximity to the wick end.
3. A portable torch, comprising a fuel supply tube, a nozzle element at the outer end of said tube, a hood enclosing the nozzle element, mounted over the tube and open at its outer end, a wick and fuel reservoir mounted on said tube and having a tubular extension projecting through the rear of said hood, and a wick extending from the tubular extension and cooperating with the nozzle element, and the hood being provided with angularly directed inlet openings in proximity to the wick end.
4. A portable torch, comprising a fuel supply tube, a nozzle element at the outer end of said tube, a hood enclosing the nozzle element, mounted over the tube and open at its outer end, a wick and fuel reservoir mounted on said tube and having a tubular extension projecting through the rear of said hood, means to adjustably secure the reservoir on said tube, and a wick extending from the tubular extension and cooperating with the nozzle element.
5. A portable torch, comprising a fuel supply tube, a nozzle element at the outer end of said tube, a hood enclosing the nozzle element, adjustably mounted over the tube and open at its outer end, a wick and fuel reservoir mounted on said tube and having a tubular extension projecting through the rear of said hood, and a wick extending from the tubular extension and cooperating with the nozzle element.
6. A portable torch, comprising a fuel supply tube, a nozzle element at the outer end of said tube, a hood enclosing the nozzle element, mounted over the tube and open at its outer end, a wick and fuel reservoir mounted on said tube and having a tubular extension projecting through the rear of said hood, means to adjustably secure the reservoir on said tube, means to adjustably secure the hood on said tubular extension, and a wick extend-

ing from the tubular extension and cooperating with the nozzle element.

7. A portable torch, comprising a fuel supply tube, a nozzle element at the outer end of said tube, a hood enclosing the nozzle element, mounted over the tube and open at its outer end and rounded at the lower portion of said outer end, a wick and fuel reservoir mounted on said tube and having a tubular extension projecting through the rear of said hood, and a wick extending from the tubular extension and cooperating with the nozzle element.

8. A portable torch, comprising a fuel supply tube, a nozzle element at the outer end of said tube, a portion of the latter immediately behind the nozzle element being coiled, a hood enclosing the nozzle element, mounted over the tube and open at its outer end, a wick and fuel reservoir mounted on said tube and having a tubular extension projecting through the rear of said hood, and a wick extending from the tubular extension and cooperating with the nozzle element.

9. A portable torch, comprising a fuel supply tube, a nozzle element at the outer end of said tube, a portion of the latter immediately behind the nozzle element being coiled, a hood enclosing the nozzle element, mounted over the tube and open at its outer end, a wick and fuel reservoir mounted on said tube and having a tubular extension projecting through the rear of said hood, and a wick extending from the tubular extension and cooperating with the nozzle element, and located in proximity to said coiled portion.

In testimony whereof I affix my signature.
